UNITED STATES PATENT OFFICE.

IGNATZ NEUBERGER, OF SAAZ, AUSTRIA-HUNGARY.

TOBACCO-PIPE.

SPECIFICATION forming part of Letters Patent No. 755,527, dated March 22, 1904.

Application filed November 2, 1901. Serial No. 80,945. (No model.)

To all whom it may concern:

Be it known that I, IGNATZ NEUBERGER, a citizen of the Empire of Austria-Hungary, residing at Saaz, Bohemia, Austria-Hungary, have invented certain new and useful Improvements in Tobacco-Pipes, of which the following is a specification.

This invention relates to improvements in tobacco-pipes, and has for its object to prevent the passage of nicotin, products of decomposition of the nicotin, as pyridin, cololidin, or the like, tarry products of distillation, and other impurities to the stem of the pipe. This is obtained by the provision in the lateral walls of the tobacco-container of perforations and slots, through the latter of which the smoke escapes to the stem, while in the former the combustion products mentioned above become deposited as the charge burns away, so as to be out of contact with the burning tobacco during smoking. The arrangement of holes and slots in the lateral wall of the container insures, moreover, a complete combustion of the tobacco, while in pipes hitherto used the layer adjoining the walls of the tobacco-container has generally only been carbonized.

In the accompanying drawings, Figure 1 shows a vertical section of a pipe-bowl provided with a tobacco-container adapted for the passage of the smoke laterally from the container. The smoke passes from the highest point of the tobacco layer. Fig. 2 is a section on the line $x-x$ of Fig. 1; and Fig. 3 is a section similar to Fig. 1, the container having been turned relatively to the pipe-bowl in such a manner that the smoke issues at a lower point.

The exit of the smoke laterally from the container is effected by the insertion into the pipe-bowl a of a socket-like cup or thimble b , which fits the bowl snugly and which is provided with a closed bottom and serves as the tobacco-container. This container b is provided with one or two slots arranged diametrically opposite to each other or with a number of slots extending spirally in a vertical direction and is provided, moreover, according to the present invention with a great number of small holes or openings d . The pipe-

bowl is provided on its inner wall with one or two diametrically opposite or with several vertically-extending grooves e .

The container b fits into the bowl a in such a manner that the walls of the two touch each other, so that the holes d and the slots c in the container are closed by the inner walls of the pipe-bowl except at the points where the slots of the pipe-bowl a and of the container b intersect. At this point (or at these points) a lateral escape-passage f (or two or more passages) is formed for the smoke. When beginning to smoke after having filled the container b with tobacco and ignited the latter, the container b is turned so that the passage for the smoke—*i. e.*, the point of intersection of the slots c and e —shall be situated as high as possible. The air and the smoke drawn in by the smoker pass in the direction shown by the arrows through the passages and down the grooves on the inside of the bowl and maintain the tobacco alight. As the tobacco is consumed and the top level sinks the container is turned a little, so that the passage for the smoke and the air becomes gradually lower until the tobacco has burned to the bottom. The slots have, therefore, for their object, first, to provide passages for the smoke and the air at the point or points of intersection; but they are also destined, as well as the small holes d in the container, to receive the combustion products of the tobacco and to prevent their being burned subsequently, whereby the sour empyreumatic and bad taste of the smoke is avoided. Besides, these holes form hollow air-spaces, close to which the burning tobacco lies, whereby a complete combustion is obtained.

The container may be made of metal, porcelain, asbestos, meerschaum, or the like. The pipe may be easily cleaned after the removal of the container, and the bottom of the pipe-bowl serves as a receptacle for the nicotin fluid, which may be poured away after the container or the stem has been removed.

The main object of the slots c and e and the perforations d are that the former coöperate to form exit-passages for the smoke and the latter act to promote combustion of the tobacco and also receive a deposit of a certain amount of the ashes as the tobacco burns away,

thus reducing the amount which would otherwise lie on the top of the burning mass.

What I claim as my invention, and desire to secure by Letters Patent, is—

- 5 1. A tobacco-pipe comprising a bowl, a downwardly-extending groove in the inner wall of said bowl, a tobacco-container with a closed bottom, fitting in said bowl a downwardly-inclined slot in the lateral wall of said container and a series of small perforations in the lateral wall of the container, substantially as described.
- 10 2. A tobacco-pipe comprising a bowl, a plu-

rality of vertical grooves in the inner wall of said bowl, a tobacco-container with a closed bottom, fitting in said bowl, a plurality of spiral slots in the lateral wall of said container and a series of perforations in lateral wall of the container, substantially as described.

In testimony whereof I have signed my name to this specification in the presence of two subscribing witnesses.

IGNATZ NEUBERGER.
